UNITED STATES PATENT OFFICE.

GEORGE LINDER AND JOHN REICH, OF MILWAUKEE, WISCONSIN, ASSIGNORS OF ONE-THIRD TO HUBERT J. ROCK, OF MILWAUKEE, WISCONSIN.

STEAM-BOILER.

SPECIFICATION forming part of Letters Patent No. 778,828, dated December 27, 1904.

Application filed April 16, 1904. Serial No. 203,402.

To all whom it may concern:

Be it known that we, GEORGE LINDER and JOHN REICH, citizens of the United States, residing at Milwaukee, county of Milwaukee, 5 and State of Wisconsin, have invented new and useful Improvements in Steam-Boilers or Water-Heaters, of which the following is a specification.

Our invention relates to improvements in 10 steam-boilers; and it pertains to the peculiar construction and relative arrangement of the several water-chambers, the chamber-connecting pipes, the combustion-chamber, and draft-passages to each other, as well as to the means 15 of forming the connecting-joints between the several water-chambers and the connecting water-pipes.

Our invention is explained by reference to 20 the accompanying drawings, in which— Figure 1 represents a front view. Fig. 2 represents a vertical section. Fig. 3 is a transverse section drawn on line *xx* of Fig. 1. Fig. 4 is a transverse section drawn on line *yy* of Fig. 1, and Fig. 5 is a transverse section drawn 25 on line *tt* of Fig. 1.

Like parts are identified by the same reference-letters throughout the several views.

A represents the supporting-base of the 30 boiler; B, the fire-grate; C, the combustion-chamber. The combustion-chamber C is surrounded on all sides by an annular water-chamber D.

Supported above the combustion-chamber 35 C is a central water-chamber E, which is connected at its front and rear sides with the chamber D by the water-pipes F F and G G. Located at the extreme upper end of the boiler is a second annular chamber H, which is supported near its outer edge from the lower annular chamber D by the annular series of pipes 40 I I, while it is connected centrally with the central chamber E by the two annular series of pipes J J. Heretofore it has been common to connect the ends of the pipes with the 45 water-chambers of boilers by screw-threaded joints or by riveting or upsetting the ends of the pipes. By our improvement the pipe-receiving apertures K of the several chambers D, E, and H are slightly tapered to fit

the tapers of said pipes, whereby when said 50 pipes are in place in the several chambers and said chambers are drawn together they form closely-fitting joints, which prevent the escape of steam or water. When constructing our 55 boiler, the several pipes connected with the lower chamber D are first put in place, when the chamber E is placed thereon. This being done, the second series of pipes above are inserted in the several apertures formed in the upper wall of the chamber E, when the upper 60 chamber H is placed upon the upper ends of the second and upper series of pipes, whereby the several chambers are connected together, as indicated in Fig. 2. This being done, the several chambers are secured firmly in place 65 upon the connecting-pipes by the several connecting-rods L. The rods L have screw-threaded bearings M in the lower inner walls of the chambers D and E and extend from thence upwardly through the pipes I and J 70 across the chamber H and protrude through the upper wall of said chamber H, at which point they are provided with fastening-nuts N, whereby when said rods K are in place 75 and said nuts N are turned down on their protruding ends said chambers H and E and D are drawn toward each other and secured firmly in place upon the ends of the connecting-pipes. To prevent the escape of steam or water from around the protruding ends of 80 the rods L, the lower sides of the nuts N taper inwardly and downwardly toward the connecting-rods, while the opposing surfaces of the water-chambers against which they bear are tapered to conform to the taper of said 85 nuts and the contiguous bearings of such parts are so ground as to form steam-tight bearings. Attention is called to the fact that by the construction described we are enabled to entirely dispense with the packing between 90 the joints of the contiguous parts, thus avoiding the defects incident to the use of packing as heretofore employed in the construction of this class of boilers.

To prevent the smoke and products of combustion from escaping too rapidly from the combustion-chamber that the fuel may be used with the greatest possible economy, we have 95

interposed a cylindrical deflecting-shell Q between the water-chambers E and H, and we also extend the smoke-flue R down into the furnace past the water-chamber H to within 5 a short distance of the upper surface of the water-chamber E, whereby the smoke and products of combustion as they escape from the combustion-chamber are first brought in contact with the lower surface of the water-chamber E, as indicated by the arrows, when 10 they are deflected downwardly and pass out between the several water-tubes of the series II, as indicated by the arrows, and from thence upwardly past the upper edge of the deflecting-shell Q until they are brought in contact with 15 the lower wall of the upper chamber H, when they are deflected downwardly and passed over the upper edge of the deflecting-shell Q until they are brought in contact with 20 the upper surface of the water-chamber E, when they pass up from beneath the lower end of the smoke-flue R and from thence to the atmosphere in the usual way, as indicated by the arrows. It will be obvious that by 25 this arrangement we have provided for the free circulation of the smoke and products of combustion past the several water-chambers and connecting-pipes, while by the arrangement of the water pipes and chambers we have 30 provided for the free circulation of the water through them and for the steam to pass from both the lower and central chamber to the upper chamber without liability of becoming trapped or otherwise retarded in its movement. 35

The deflecting-shell Q is provided with an aperture S, which is closed with a door T, whereby access to the inner series of tubes J may be had for the purpose of cleaning the 40 same.

Heretofore it has been common to inclose the furnace with a single continuous shell extending entirely around the same from one side of the door to the other. By our improvement, however, we form the inclosing shell in two separate parts U, which are connected with the frame V of the front doors by hinges W, whereby when desirous to clean the furnace we are enabled to swing the respective shells U U toward the right and left to readily reach all the pipes and water-chambers for such purpose. This being done, said inclosing shells U are swung back in place and secured together. 50

55 Having thus described our invention, what we claim as new, and desire to secure by Letters Patent, is—

1. In a steam-boiler the combination of a lower annular water-chamber the central aperture of which forms a combustion-chamber; an upper annular water-chamber the central aperture of which forms a smoke-passage; a central water-chamber forming a deflecting-partition between said lower and upper 60 chambers; a plurality of water-pipes commu-

nicating between the respective chambers and an exterior wall inclosing said chambers and pipes.

2. In a steam-boiler the combination of a lower annular water-chamber the central aperture of which forms a combustion-chamber; an upper annular water-chamber the central aperture of which forms a smoke-passage; a central water-chamber forming a partition between said upper and lower chambers; a plurality of water-pipes communicating from said lower annular chamber to said central chamber; a plurality of water-pipes communicating from said central chamber to said upper chamber; a plurality of water-pipes 70 communicating from said lower chamber directly to said upper chamber past said central chamber; an exterior wall inclosing said chambers and pipes. 75

3. In a steam-boiler a supporting-base forming an ash-receptacle; a lower annular water-chamber supported on said base, the central aperture of which forms a combustion-chamber; a fuel-supporting grate located at the bottom of said combustion-chamber; an upper 80 annular water-chamber, the central aperture of which forms a smoke-passage; a central chamber forming a partition between said upper and lower chambers; water-pipes communicating from said lower annular chamber to 85 said central chamber; water-pipes communicating from said central chamber to said upper chamber; water-pipes communicating from said lower chamber to said upper chamber directly past said central chamber and an 90 exterior wall inclosing said chamber and pipes. 95

4. In a steam-boiler, the combination of a lower annular water-chamber the central aperture of which forms a combustion-chamber; an upper annular water-chamber, the central 100 aperture of which forms a smoke-passage; a central water-chamber forming a deflecting-partition between said lower and upper chambers, said chambers being provided with a plurality of tapered apertures for the reception of the ends of the connecting water-pipes; a plurality of water-pipes tapered at their ends to conform to the apertures formed therefor in said water-chambers and means for binding and connecting said chambers together. 105

5. In a steam-boiler, the combination of a lower annular water-chamber the central aperture of which forms a combustion-chamber; an upper annular water-chamber the central aperture of which forms a smoke-passage; a central water-chamber forming a partition between said upper and lower chambers; a plurality of water-pipes communicating from said lower annular chamber to said central chamber; a plurality of water-pipes communicating from said central chamber to said upper chamber; a plurality of water-pipes 115 communicating from said lower chamber directly to said upper chamber past said central chamber; an exterior wall inclosing said chamber; 120 an exterior wall inclosing said chamber and pipes. 125

65

bers and pipes; an annular vertical smoke-deflecting partition supported from said central water-chamber between the exterior and interior series of water-pipes, substantially as set forth.

6. In a steam-boiler, the combination of a lower annular water-chamber the central aperture of which forms a combustion-chamber; an upper annular water-chamber the central aperture of which forms a smoke-passage; a central water-chamber forming a partition between said upper and lower chambers; a plurality of water-pipes communicating from said lower annular chamber to said central chamber; a plurality of water-pipes communicating from said central chamber to said upper chamber; a plurality of water-pipes communicating from said lower chamber directly to said upper chamber past said central

chamber; an exterior wall inclosing said chambers and pipes; an annular vertical smoke-deflecting partition supported from said central water-chamber between the exterior and interior series of water-pipes; a central annular vertical partition suspended from said upper water-chamber terminating at its lower end near said central water-chamber and adapted to serve as a deflector for retarding the escape of heat and products of combustion from the boiler, substantially as set forth. 20 25 30
